(57) **CLAIM**

The ornamental design for a fluorescent lampholder, as shown and described.

DESCRIPTION

FIG. 1 is a top perspective view of a fluorescent lampholder incorporating our new design;

FIG. 2 is an exploded top perspective view of the fluorescent lampholder illustrated in FIG. 1, showing a lens portion and a base portion thereof;

FIG. 3 is a top plan view of the fluorescent lampholder illustrated in FIG. 1, showing the lens portion and the base portion thereof separated;

FIG. 4 is a bottom plan view of the fluorescent lampholder illustrated in FIG. 1, showing the lens portion and the base portion thereof;

FIG. 5 is a front elevational view of the fluorescent lampholder illustrated in FIG. 1;

FIG. 6 is a rear elevational view thereof;

FIG. 7 is a right side elevational view thereof;

FIG. 8 is a left side elevational view thereof;

FIG. 9 is a front elevational view of the fluorescent lampholder illustrated in FIG. 1, showing the lens portion and the base portion thereof separated;

FIG. 10 is a rear elevational view of the fluorescent lampholder illustrated in FIG. 9;

FIG. 11 is a right side elevational view of the fluorescent lampholder illustrated in FIG. 9; and,

FIG. 12 is a left side elevational view of the fluorescent lampholder illustrated in FIG. 9.
